UNITED STATES PATENT OFFICE.

ALBERT A. HARVIE, OF OTTUMWA, IOWA.

KNOCKDOWN CARPENTER'S SQUARE.

1,049,298.

Specification of Letters Patent. Patented Dec. 31, 1912.

Application filed February 3, 1912. Serial No. 675,335.

To all whom it may concern:

Be it known that I, ALBERT A. HARVIE, a citizen of the United States, residing at Ottumwa, in the county of Wapello and 5 State of Iowa, have invented certain new and useful Improvements in Knockdown Carpenters' Squares, of which the following is a specification.

This invention relates to an improved 10 form of carpenters' square of such construction that the tongue can be removed from the blade in an extremely simple manner, but nevertheless of such construction that when the tongue and blade are assembled 15 they will be held firmly and rigidly and will be accurately positioned with respect to each other.

One of the main objects of the invention is to so construct the tongue and blade that 20 when they are disassembled each will comprise merely a straight bar of metal, so that the two parts can be easily packed into a carpenter's tool box or other carrier.

Another object is to provide a novel form 25 of locking means, whereby the tongue and blade will not only be held rigidly together but will be instantaneously and accurately positioned, both to secure proper angular relation between them and to position the 30 tongue lengthwise of its dimension accurately with respect to the blade. By this I mean that the end of the tongue shall project exactly the proper distance from the edge of the blade.

Another object is to so construct the parts 35 that by merely turning one or more screws of the lock, the aforementioned accurate positioning shall be secured, and so that at the same time a clamping effect will be obtained, so that the parts may be clamped 40 together with the same degree of force, regardless of any slight wear which may take place, because the screw or screws may always be rotated until tight.

Other objects and uses will appear from 45 a detailed description of the invention, which consists in the features of construction and combination of parts hereinafter described and claimed.

In the drawing, Figure 1 shows a top view 50 of the face of my improved square, the tongue and blade being assembled and having their end portions broken away; Fig. 2 shows a top view of the inner end of the 55 tongue; Fig. 3 shows a top view of the inner end of the blade; Fig. 4 shows a section taken on line 4—4 of Fig. 1, looking in the

direction of the arrows; and Fig. 5 shows a section taken on line 5—5 of Fig. 1, looking in the direction of the arrows. 60

In the drawing, the tongue is designated by the numeral 6 and the blade by the numeral 7. The blade is provided across the upper face of its inner end with a groove or slot 8 adapted to receive the end portion 65 9 of the tongue. This groove has its outer edge face 10 undercut, as shown more particularly in Figs. 4 and 5, the edge face 11 of the end of the tongue being correspondingly beveled, so that when the two elements 70 are set together the tongue cannot be raised unless at the same time it be allowed to move sidewise. The edge face 12 of the groove is beveled or slanted substantially 75 parallel to the edge face 10 thereof, and the edge face 13 of the tongue is correspondingly undercut. By this construction, if the face 14 of the tongue be forced downwardly into the groove, the tongue will at the same time be forced sidewise so as to insure a 80 tight engaging of the edge face 11 of the tongue into the dovetailed edge face 10 of the groove. Now, in order to secure a better clamping, and in order to give the parts a certain amount of spring action, the surface 85 of the groove is preferably arched or rounded a certain amount, as shown in Figs. 4 and 5, so that the central portion 15 of the groove shall be higher than its sides 16 and 17. At the same time the end of the tongue 90 should be of such width with respect to the groove that its edge faces 11 and 13 will clamp against the corresponding edge faces 10 and 12 of the groove before the lower surface 18 of the tongue contacts the surface 95 16 of the groove. By thus proportioning the parts, a certain amount of spring action can be secured and the tongue can be brought into firm and accurate register with the groove, until the edge faces of the tongue 100 and groove may have worn in service to a considerable extent, so that the surfaces 16 and 18 shall ultimately come into contact. In other words, by thus proportioning the parts, the same degree of accuracy and the 105 same amount of clamping force can be secured, even though the parts wear to a considerable extent.

Obviously, any suitably formed clamping means may be adopted for drawing the end 110 of the tongue down into the groove. In the present instance, I adopt screw-threaded studs, designated 19 and 20 respectively, which thread into the blade at a point

alongside of the groove and have their heads 21 beveled outwardly to such an extent that they may overlie the edge face 12 of the groove. Each stud is provided with 5 a hole 22, into which may be seated a key of suitable form to rotate the stud and thus clamp the end of the tongue into the groove. Now, if each stud were formed with its head completely circular, it would be necessary to practically remove the studs before 10 the tongue could be withdrawn from the groove.

In order to simplify the process of setting up the square, or knocking it down, I 15 cut away a portion 23 of the bevel of each stud, so that by rotating the studs into the position shown in Fig. 3 simply a partial rotation, the tongue can be immediately withdrawn without having to completely 20 remove the studs. I also provide means for accurately spacing or positioning the tongue, so that its markings will occupy a predetermined distance from the edge 24 of the blade. To this end I cut the grooves 25 25 in the edge of the tongue so that the latter must be properly positioned in the groove before the studs can be rotated to lock the parts together, as unless such positioning is effected it will be impossible to 30 rotate the studs. Therefore, the studs perform a three-fold purpose: they serve to hold the end of the tongue in the groove; they serve to clamp the parts together; and they also serve to accurately position the 35 tongue within the groove and to prevent its withdrawal therefrom in an endwise direction.

In order to provide a flush edge 26 at the point where the edge of the tongue lines 40 up with the groove, I provide a shoulder 27 in the tongue. By this means, the two elements, when assembled, will constitute a perfectly accurate square or other instrument, although when disassembled each element will be virtually a straight bar of metal.

It will be seen that the head of each screw has that portion which overlies the tongue beveled, so that as the screw is rotated 50 it serves not only to clamp the tongue into the groove but also tends to force the tongue sidewise, and thus make the undercut of the groove still more effective to hold the two members solidly together.

While I have herein designated the member 6 as the tongue and the member 7 as the blade, still it would be evident that the terminology might be reversed, or that the mechanical arrangement might be reversed, 55 in either of which cases the groove or slot would be formed in the tongue instead of in the blade. In either case the mechanical arrangement and operation would be sub-

stantially the same as that herein shown and described.

65

I claim:

1. In a device of the class described, the combination of a blade having a single socket formed in one of its surfaces, and having opposite edge faces of said socket 70 undercut and beveled respectively in substantially parallel planes, a tongue having a single portion adapted to seat into the socket of the blade and having opposite edge faces of said portion beveled and undercut to seat against the undercut and beveled faces of the socket respectively, and means for clamping the undercut edge face of the tongue toward the beveled edge face of the socket of the blade, to thereby force 80 the tongue sidewise to bring its beveled edge face into solid engagement with the undercut edge face of the socket of the blade, substantially as described.

2. In a device of the class described, the combination of a blade having a socket extending in from one surface and having parallel edge surfaces of said socket undercut and beveled respectively in substantially parallel planes, a tongue having a portion 90 adapted to seat into said socket and having parallel edge faces beveled and undercut to engage the undercut and beveled edge faces of the socket respectively, and means for clamping the undercut edge face of the 95 tongue toward the beveled edge face of the socket of the blade to thereby exert a side pressure on the tongue to force its beveled edge face securely against the undercut edge face of the socket of the blade, substantially 100 as described.

3. In a device of the class described, the combination of a blade having a single socket extending inwardly from one of its surfaces and having an undercut edge face 105 and a beveled edge face, a tongue having a single portion adapted to seat in the socket of the blade and having edge faces beveled and undercut to correspond with the undercut and beveled edge faces of the 110 socket of the blade respectively, and a beveled headed member screw-threaded into the blade and having a beveled portion of its head overlying a portion of the side of the tongue adjacent the undercut edge face of 115 the same to force said edge face toward the beveled edge face of the socket of the blade and to simultaneously exert a side pressure on the tongue for forcing the same sidewise to bring its beveled edge face into firm contact with the undercut edge face of the 120 blade, substantially as described.
